UNITED STATES PATENT OFFICE.

EUGENE H. PECK, OF MERIDEN, CONNECTICUT.

MACHINE FOR ORNAMENTING GLASS.

SPECIFICATION forming part of Letters Patent No. 247,515, dated September 27, 1881.

Application filed July 22, 1881. (No model.)

To all whom it may concern:

Be it known that I, EUGENE H. PECK, of Meriden, in the county of New Haven and State of Connecticut, have invented certain new and useful Improvements in Machines for Ornamenting Glass; and I do hereby declare that the following is a full, clear, and exact description of the invention, which will enable others skilled in the art to which it appertains to make and use the same, reference being had to the accompanying drawings, which form a part of this specification.

Figure 1 is a vertical sectional view. Fig. 2 is a horizontal sectional view on the line xx , Fig. 1; and Fig. 3 is a side view of a vase or other article the edge of which has been scalloped or ornamented by my improved machine.

Corresponding parts in the several figures are denoted by like letters of reference.

20 This invention relates to a machine for scalloping or otherwise ornamenting the edges of hollow glassware, the construction and operation of which will be hereinafter fully described, and particularly pointed out in the claims.

25 Referring to the drawings hereto annexed, A represents the hollow cylindrical stem or body, which rests upon the base B of the machine. The said stem may be cast in one piece with the base or made separate, as circumstances may require. The upper end of the cylinder or stem A has a flange, C, upon which the bed D of the machine is placed. Said bed is provided with a cone or frustum, E, upon which the vase or other article to be ornamented 30 may be temporarily adjusted and supported.

35 F and G represent two sleeves, which are adjusted upon the stem A. Said sleeves are provided with radial arms or spokes J K, as clearly shown in Fig. 2 of the drawings hereto annexed.

40 To the arms J of the upper sleeve, F, are pivoted levers L, provided at their lower ends with eccentric slots M, working upon studs N, formed or secured upon the sides of the arms K of the lower sleeve, G. The latter, which is capable of sliding vertically upon the stem or standard A, is operated by means of a forked lever, O, pivoted to a bracket, P, and having the ends of the prongs Q slotted at R and adjusted upon studs S on diametrically-opposite

sides of the sleeve G, which may thus be raised or lowered, so as to operate the levers L. The lever O may be operated by hand or foot power, whichever may be found most convenient. The upper ends of the levers L are jointed to 55 carriages T, which slide radially in suitable grooves or slots in the table or bed D. Said carriages or slides carry cutters or punches U, secured by means of screws V, so as to be capable of being removed when others of a different shape are to be substituted. The sides of the cone or frustum E are provided with recesses W, of a shape corresponding with the cutters U; and the said cone or frustum is to be made removable, in order that a different one 60 may be substituted when necessary.

65 From the foregoing description, taken in connection with the drawings hereto annexed, the operation and advantages of my invention will be readily understood. The vase or other blank, while hot, is adjusted upon the frustum E, when by operating the lever O the cutters herein described are caused to remove portions of the edge of the vessel, which is thus scalloped or ornamented.

70 I am aware of the patent to R. Voigt, No. 228,495, of June 8, 1880, and I claim nothing therein shown; but,

75 Having thus described my invention, I claim and desire to secure by Letters Patent of the United States—

1. In a machine for scalloping glass, constructed substantially as described, the combination, with the stem A, of the sleeve F, the sliding sleeve G, and the levers L, pivoted to 80 spokes of sleeve F, and having eccentric slots adjusted upon studs on the spokes of the movable sleeve G, as herein shown and specified.

2. The combination of the stem A, the bed D, having cone or frustum E, the levers L, the 85 sliding sleeve G, and the operating-lever O, substantially as and for the purpose set forth.

In testimony that I claim the foregoing as my own I have hereunto affixed my signature in presence of two witnesses.

EUGENE H. PECK.

BENJ. PAGE,
LEROY C. PARDEE.

Corrections in Letters Patent No. 247,515.

It is hereby certified that in Letters Patent No. 247,515, issued September 27, 1881, to Eugene H. Peck, for an improvement in "Machines for Ornamenting Glass," the reference letter "G," in lines 88 and 91 of the printed specification attached to and forming a part of the said Letters Patent, was erroneously printed "I;" that the proper corrections have been made in the files and records pertaining to the case in the Patent Office, and are hereby made in said Letters Patent.

Signed, countersigned, and sealed this 18th day of October, A. D. 1881.

[SEAL.]

A. BELL,
Acting Secretary of the Interior.

Countersigned:

E. M. MARBLE,
Commissioner of Patents.
